UNITED STATES PATENT OFFICE.

EDWIN C. HARNDEN, OF CARBONDALE, PENNSYLVANIA.

DEVICE FOR MOVING GRAIN.

SPECIFICATION forming part of Letters Patent No. 563,172, dated June 30, 1896.

Application filed November 15, 1895. Serial No. 569,076. (No model.)

To all whom it may concern:

Be it known that I, EDWIN C. HARNDEN, of 5
Carbondale, in the county of Lackawanna
and State of Pennsylvania, have invented a
new and Improved Device for Moving Grain,
&c., of which the following is a full, clear,
and exact description.

The object of the invention is to provide a
new and improved device for moving grain
from one place to another, the device being
very simple and durable in construction, very
effective in operation, and more especially
designed for unloading grain and other loose
material contained in cars.

15 The object of the invention consists prin-
cipally of a revoluble drum, a pulling-rope
adapted to wind on the said drum and con-
nected with the scoop, shovel, or like device
for moving grain, a clutch mechanism for
20 throwing the drum into and out of gear, and
a controlling-rope adapted to wind on the
said drum and under the control of the op-
erator said controlling-rope controlling the
clutch mechanism.

25 The invention also consists of certain parts
and details, and combinations of the same, as
will be fully described hereinafter, and then
pointed out in the claims.

Reference is to be had to the accompanying
30 drawings, forming a part of this specification,
in which similar characters of reference in-
dicate corresponding parts in both the views.

Figure 1 is a plan view of the improvement
as applied and with the car and building in
35 section, and Fig. 2 is a sectional side eleva-
tion of the same.

The improved device, as illustrated in the
drawings, is arranged in a building A, pro-
vided on its outside with a receiving-spout
40 B, into which the grain is moved from the
interior of the railroad-car C by means of a
scoop, shovel, or like device D. On the bail
D' of the scoop D is secured one end of a
pulling-rope E, passing over the horizontally-
45 disposed pulley F, journaled on a suitable
stud held in the car-door opening, as is plainly
shown in the drawings, the rope then extend-
ing through an opening in the side of the
building A, over a pulley F', to finally wind
50 on a drum G, held loosely on a shaft H, jour-

naled in suitable bearings within the build-
ing A.

On the shaft H is fastened a pulley I, con-
nected by a belt I' with suitable machinery
to impart a rotary motion to the said shaft H. 55
The drum G is adapted to be connected by a
beveled jaw-clutch J with the shaft H, so
that when the latter is rotated the rotary mo-
tion is given to the drum G, and the rope E is
then wound up on the said drum by power 60
and a pull is exerted on the scoop D to move
the latter to the door-opening of the car, and
to permit the operator to empty the contents
of the scoop into the spout B.

The clutch mechanism is controlled by a 65
shifting lever K, fulcrumed at its rear end
at K' and drawn on by a spring L to nor-
mally hold the drum out of engagement with
the clutch. On the free end of the shifting
lever K is journaled a pulley N, over which 70
passes the controlling-rope O, also passing
over a pulley P within the building A to wind
on the drum G. The rope after leaving the
pulley N passes over a second pulley P' and
then extends through the opening in the 75
building A, to pass over a pulley P'', held on
the stud for the pulley F. The rope then ex-
tends into the car C to connect with the han-
dle D' of the scoop D and under the control
of the operator manipulating the scoop. 80

Now, it will be seen that when the operator
pulls on the controlling-rope O, as shown in
Fig. 1, he exerts a pull on the shifting lever
K, so that the latter is swung to the left to
engage the drum G, by means of the clutch 85
J, with the shaft H to cause the drum G to
revolve to wind up the pulling-rope E. As
the latter winds up, the scoop D is pulled for-
ward with its load until it passes out at the
car-door opening, when the contents of the 90
scoop are dumped into the spout B, as pre-
viously explained. When this is done, the
operator releases the pull on the rope O, so
that the push of the beveled face of the jaw
of the clutch and the pull of the spring L re- 95
turn the shifting lever K to its normal posi-
tion, to throw the drum G out of gear with the
shaft H. When the scoop D is emptied, as
previously explained, the operator draws the
scoop back in the car to again engage it with 100

the grain to fill the scoop, after which he again pulls on the rope O to throw the drum G in gear with the shaft H. The rope E is now again wound up and the above-described operation is repeated.

It is understood that when the operator moves the empty scoop D back in the car he unwinds both ropes E and O, the drum G then revolving loosely in an opposite direction on the shaft H.

Having thus described my invention, I claim as new and desire to secure by Letters Patent—

1. A device of the class described, comprising a revoluble drum, a pulling-rope adapted to wind on the said drum and connected with a scoop, shovel or like device for moving the grain, a clutch mechanism for throwing the drum into and out of gear, and a controlling-rope adapted to wind on the said drum and under the control of the operator, the said controlling-rope being connected with the clutch mechanism to operate the latter, substantially as shown and described.

2. A device of the class described, comprising a revoluble shaft, a drum mounted loosely thereon, a pulling-rope adapted to wind on the drum and connected at its outer end with a

scoop, shovel or like device for moving the grain, a clutch mechanism for connecting the said drum with the said shaft, a shifting lever connected with the said clutch mechanism, and a controlling-rope connected with the said shifting lever and adapted to wind on the said drum, the rope being under the control of the operator, substantially as shown and described.

3. A device of the class described, comprising a revoluble shaft, a drum mounted loosely thereon, a pulling-rope adapted to wind on the drum and connected at its outer end with a scoop, shovel or like device for moving the grain, a clutch mechanism for connecting the said drum with the said shaft, a shifting lever connected with the said clutch mechanism, a controlling-rope connected with the said shifting lever and adapted to wind on the said drum, the rope being under the control of the operator, and a spring connected with the said shifting lever to return the latter to its normal position when the controlling-rope is released, substantially as shown and described.

EDWIN C. HARNDEN.
